Patented May 8, 1917.

UNITED STATES PATENT OFFICE.

HORACE INMAN AND FRANK M. JOSLIN, OF AMSTERDAM, NEW YORK, ASSIGNEES TO
INMAN MANUFACTURING COMPANY, INCORPORATED, OF AMSTERDAM, NEW YORK,
A CORPORATION OF NEW YORK.

MACHINE FOR MAKING PAPER BOX-BLANKS.

1,225,131.

Specification of Letters Patent.

Patented May 8, 1917.

Application filed July 29, 1912. Serial No. 712,130.

To all whom it may concern:

Be it known that we, HORACE INMAN and FRANK M. JOSLIN, citizens of the United States, residing at Amsterdam, in the county 5 of Montgomery and State of New York, have invented certain new and useful Improvements in Machines for Making Paper Box-Blanks, of which the following is a specification.

10 This invention relates to machines for making paper box blanks and more particularly to machines of this class which form the web from a plurality of layers of paper, print the web and die and crease the blanks 15 so that the blanks as delivered from the machine are ready to be folded to form a completed box.

One of the objects of the invention is to provide a machine of this class which is 20 capable of forming box blanks from a comparatively heavy web and in which the web moves continuously from one end of the machine to the other without interruption. In a machine of this character, where the web 25 is formed of thick paper, the rolls as received from the paper mill are very large and heavy so as to provide a very long strip, and thereby avoid frequent renewals of the rolls, so that the machine may be operated 30 continuously for considerable periods of time.

A further object of the invention is to provide a machine in which the web is made into box blanks immediately after being 35 formed and while moist so that the outer surfaces or coatings of the web will not be broken in forming the creases in the blank.

Other objects and the features of novelty 40 will be apparent from the following description taken in connection with the accompanying drawings, in which,

Figure 1 is a side elevation of the machine;

Fig. 2 is a plan;

5 Fig. 3 is a longitudinal section of the printing mechanism;

Fig. 4 is an enlarged section on the line 6-6 of Fig. 1, and

50 Fig. 5 is a plan of the box blank as formed by the creasing and dieing mechanism.

Referring to the drawings, A designates generally the web-forming mechanism, B the printing mechanism and C the dieing and scoring mechanism.

The web-forming mechanism comprises a 55 suitable frame 10, on which may be supported in suitable bearings 11 the spindles 12 and 13, which carry the rolls of paper *a* and *b* respectively. The bearings 11 may be of ordinary construction but are preferably 60 provided with means for adjustment whereby the rolls of paper may be properly alined.

In the drawings we have shown an additional roll of paper *c*, carried by a spindle 65 14, this spindle being mounted in suitable bearings 15, carried by the pedestals 16.

The frame 10 supports a paste-tank 17, bearings 18 for a guide-roller 19, and brackets 20 which carry a guide-roller 21, 70 the latter roller being preferably arranged to be vertically adjustable by means of the usual rack and pinion actuated by a hand-wheel 22. The frame 10 also supports the pedestals 23 and 24. The pedestal 23 supports a pair of squeezing rollers 23', these rollers being preferably supported by any suitable mechanism permitting the upper roller to be adjusted vertically. The pedestals 24, carry two pairs of pressure rolls 25 80 and 26, the upper roll of each pair being preferably vertically adjustable. The pedestals 24 also carry a guide-roller 27. The lower roll of the pressure rolls 26 may be driven from the printing mechanism by 85 means of a chain 28 and a sprocket 29, the latter being on one end of the shaft of the lower roll. On the opposite end of this shaft is a gear 30, which drives the lower roll of the pair of rolls 25 by means of a 90 gear 31 on the shaft of the lower roll and an intermediate gear 32, which meshes with the gears 30 and 31.

The pairs of rolls 25 and 26 serve as feeding rolls as well as means for pressing the 95 strips together. The paper from the roll *b* unwinds from the top of the roll and as clearly shown in Fig. 1, passes over a guide-roller 33 mounted on the top of the pedestals 23, and under the guide-roller 27. The 100 paper from the roll *a* is unwound from the bottom of the roll and passes under a guide-roller 34 and over the guide-roller 19 and from the latter into the paste-tank 17 and under the guide-roller 21. The paste-tank 105 is provided with sufficient paste to cover the guide-roller 21 so that the paper in passing through the tank will have both sides there-

of thoroughly coated with paste. From the roller 21 the paper passes through the squeezing rolls 23' and then between the pairs of pressure rollers 25 and 26. The 5 paper from the roll *c* is unwound from the bottom thereof and also passes under the guide-roller 34. From the guide-roller 34 this paper passes over a guide-roller 35 and under a guide-roller 36 and from the latter 10 to the pressure-rollers 25 and 26.

It will thus be seen that the three strips will be brought together in the pressure rolls with the strip from the roll *b* above the strip from the roll *a* and the strip from 15 the roll *c* below the strip from the roll *a*. The strips from the rolls *b* and *c* in passing though the pressure rolls will be caused to adhere to the strip from the roll *a*, owing to the fact that the latter is coated with paste 20 on both sides in passing through the paste-tank. When the web emerges from the pressure rolls 26 it will be in the form of a comparatively stiff board with the three strips firmly secured together.

25 The printing machine consists essentially of a type roll 37, supported by means of suitable bearings and arranged above a platen 38. The type on the roll 37 may be inked by any suitable inking mechanism 39.

30 When the blanks are to be printed in one color only a single type roll 37 is necessary, but when two or more colors are to be employed in printing there are provided separate type rolls and platens for each color.

35 In the drawings we have illustrated a machine adapted to print two colors and have shown two type rolls 37 and platens 38. In order to drive the type rolls each may be provided with a gear 39', which meshes 40 with a gear 40 on the shaft of the corresponding platen. The gears 40 may be driven by means of a gear 41 which is suitably supported on the frame of the machine and driven by means of a pinion 42 on a 45 shaft 43, this shaft being preferably driven by means of a pulley 44 from any suitable source of power. The printing mechanism may be provided with a pair of feed rollers 45 which may be driven by means of the

50 gears 46 from one of the gears 40 by means of an intermediate gear 47. A sprocket 48 may be arranged on the shaft of one of the feed rollers 45, this sprocket driving the chain 28. At the opposite end of the printing mechanism from the feed rollers 45 may be arranged one or more pairs of longitudinal creasing rolls 49, these rolls being preferably driven by means of gears arranged in a manner similar to that of the driving 55 gears for the feeding rolls just described.

The web is fed from the web-forming mechanism to the printing rolls by means of the feed rolls 45 and from the printing rolls passes through the creasing rolls 49, which 60 form the longitudinal creases *w* in the

blanks, and from the creasing rolls into the dieing and cross creasing mechanism.

The dieing and cross creasing mechanism consists of a frame 50 on which run the die carriages 51, 52, 53 and 54. The frame 50 carries the four upright guides 55 which are connected together at their tops by means of a suitable frame 56. The cross heads 57 are arranged above the carriages 51, 52, 53 and 54 and provided with suitable sleeves 58 75 which loosely engage the upright guides 55 whereby the cross heads are adapted to be reciprocated vertically. The frame 50 carries shafts 59 which have arranged at their ends the crank disks 60 having the crank pins 61. The crank pins 61 are connected with the cross heads 57 by means of connecting rods 62, these rods engaging suitable pins 63 on the cross heads. By this arrangement it will be seen that the cross heads will 80 be reciprocated vertically by rotating the shafts 59. In order to rotate the shafts 59 they may be provided with sprocket wheels 64, connected by a chain 65. The shaft 59 nearest the printing mechanism may be provided with a sprocket 65' which may be driven from the printing mechanism by means of a chain 66. In order to drive the chain 66 a shaft 67 is arranged on the frame of the printing mechanism and provided 85 with a sprocket 68 which may be driven from a sprocket 69 on the shaft of one of the type rolls 37 by means of a chain 70.

90 Each of the carriages 51, 52, 53 and 54 carries a bed-plate 71 and these plates are connected together by means of the longitudinally extending bars 72, arranged at the opposite ends of the bed-plates and provided with slots 73 and suitable securing bolts 74 whereby the position of the carriages may be adjusted along the bars 72. The frame 50 supports a shaft 75 by means of bearing brackets 76 and this shaft is driven by means of a sprocket 77 and chain 78 from the shaft 67. At the ends of the 105 shaft 75 are arranged the wheels 79 which carry the crank pins 80. The pins 80 are connected with pins 81 on the bars 72 by means of the connecting rods 82 so that when the shaft 75 is rotated the carriages 110 51, 52, 53 and 54 will be simultaneously moved back and forth on the frame 50.

115 The inner sides of the cross heads 57 are provided with suitable roll grooves 83 in which are arranged the rolls 84 at the ends 120 of the die plates 85.

125 Secured to the opposite ends of the bed plates 71 are the upright guide-posts 86 which pass through and loosely engage suitable openings in the die plates 85, these uprights 86 serving as vertical guides for the die plates. Owing to the arrangement of the rolls 84 in the grooves 83 in the cross heads it will be seen that the die plates 85 are also permitted to move longitudinally 130

of the cross heads with the bed plates 71 which are mounted on the carriages 51, 52, 53 and 54.

5 A pair of feed rolls 87 is arranged at the delivery end of the mechanism and preferably have a peripheral speed slightly greater than the speed of the web whereby these rolls are adapted to quickly discharge the blank from the machine after the same has 10 been severed from the web.

The operation of the dieing mechanism is as follows: The rotation of the shafts 59 causes the cross heads 57 and the die plates 85 to be reciprocated vertically and the rotation of the shaft 75 causes the carriages 15 51, 52, 53 and 54 with their bed plates 71 and the die plates 85 to be reciprocated horizontally. The speed of the shaft 75 is preferably such that when the cranks 80 are 20 moving substantially in a horizontal plane, which occurs when the cranks are directly above and below the shaft 75, the velocity of the carriages will be substantially equal to the velocity of the web. The mechanism for vertically reciprocating the die plates 85 25 is so timed that when the carriages are moving in the direction of movement of the web and at substantially the same velocity as the web the dies will come into operation 30 and simultaneously cut the notches *x* and make the cross scores *y* and sever the blank from the web by making the cut *z*. Owing to the fact that the dies are traveling with the web at the time they come into engagement with the web it will be seen that the blank may be formed without interrupting the movement of the web. This is of especial advantage in a machine of this kind which makes the blanks from a web of heavy 35 material and utilizes the large rolls of paper *a*, *b* and *c*. It will be readily understood that it is impracticable to start and stop the rolls every time a blank is formed and therefore by providing the mechanism above described this difficulty has been overcome by 40 having the dies move with the web when they form the blank. In box blank making machines the blank has usually been severed from the web heretofore by means of knives 45 arranged transversely of the web and carried by a rotating shaft. While this construction which has been heretofore used has been more or less satisfactory for thin webs, yet it cannot be used for thick webs 50 and therefore by providing a cutting die which has a movement at right angles to the web, we are able to sever the blank from the web by a clean perfectly square cut. The cross-creasing and dieing mechanism 55 above described is the sole invention of Frank M. Joslin and is claimed in application No. 712,127, filed July 29, 1912.

60 From the foregoing description it will be seen that we have provided a machine which 65 is adapted to form a continuously moving

web which is printed and formed into blanks without interrupting the movement thereof.

It will be obvious that the printing mechanism may be omitted and that the web may be cut into strips by the dieing mechanism. 70

We have also arranged the pressure rolls 25 and 26, the printing rolls and the dieing and scoring mechanism so that the web is maintained perfectly flat in traversing the machine and therefore the blanks as formed 75 are smooth and without wrinkles.

Having thus described our invention what we claim is:

1. In a machine of the class described, the combination of mechanism for forming 80 and continuously moving a heavy substantially non-flexible web; printing mechanism and reciprocating creasing and dieing mechanisms, said printing and creasing and dieing mechanisms being adapted to operate 85 on the web while the latter is in motion and in a damp or moist condition.

2. In a machine of the class described, the combination of mechanism for forming and continuously moving at a uniform velocity, 90 a heavy substantially non-flexible web, printing mechanism and reciprocating creasing and dieing mechanisms, said printing and creasing and dieing mechanisms being adapted to operate on the web while the latter is in motion and in a damp or moist condition. 95

3. In a machine of the class described, the combination of mechanism for forming and continuously moving a heavy substantially non-flexible web and reciprocating creasing and dieing mechanisms, said creasing and dieing mechanisms being adapted to operate on the web while the latter is in motion and in a damp or moist condition. 100

4. In a machine of the class described, the combination of mechanism for forming and continuously moving at a substantially uniform velocity a heavy substantially non-flexible web, and reciprocating creasing and dieing mechanisms, said creasing and dieing mechanisms being adapted to operate on the web while the latter is in motion and in a damp or moist condition. 110

5. In a machine of the class described, the combination of mechanism for forming a heavy substantially non-flexible web, reciprocating creasing and dieing mechanisms operable on the web in a damp or moist condition, and means for moving the web 115 through said mechanisms continuously and at a uniform velocity. 120

6. In a machine of the class described, the combination of mechanism for forming a heavy substantially non-flexible web, printing mechanism, reciprocating creasing and dieing mechanisms, said printing and creasing and dieing mechanisms operable on the web in a damp or moist conditioned and being so arranged that the web is main- 125 130

tained in substantially the same plane in passing through the machine, and means for moving the web through said mechanisms continuously.

5 7. In a machine of the class described, the combination of a mechanism for forming and continuously moving a heavy substantially non-flexible web in a damp condition, printing mechanism operable on said damp 10 web while it is in motion, creasing and slitting mechanism also operable on said damp web while it is in motion, and means for connecting the printing and the creasing and slitting mechanisms so that they operate in timed relation to register the printed matter and the creases.

8. In a machine of the class described, the combination of rotary printing mechanism, means for continuously feeding a heavy substantially non-flexible web in a damp condition to said printing mechanism, creasing and slitting mechanism, means carried by said printing mechanism for forwarding the web to the creasing and slitting mechanism, 25 the latter mechanism adapted to operate on said damp web while it is in motion, and said mechanisms being connected to operate in timed relation so that the printed matter

and the creases and slits in the web will register.

9. A machine of the class described comprising printing mechanism adapted to print in one or more colors, mechanism driven from the printing mechanisms for forming a continuous web in a damp condition and for forwarding the same to the printing mechanism, creasing and slitting mechanism operable on the web while in a damp condition and driven from the printing mechanism, and means for forwarding the web from the printing mechanism to the creasing and slitting mechanism.

10. A machine for forming blanks from heavy substantially non-flexible sheet material comprising means for feeding continuously and at a uniform speed a moist web of the sheet material and means for creasing and slitting said web while it is moist and in motion.

In testimony whereof we affix our signatures in presence of two witnesses.
